INVENTOR
Karl Bauer
BY
George C. Heinricke
ATTORNEY

UNITED STATES PATENT OFFICE

KARL BAUER, OF BRONX, NEW YORK

OBSERVATION DEVICE

Application filed November 3, 1928. Serial No. 316,993.

This invention relates to improvements in observation devices for doors, walls or the like, so-called spy- and peep-openings, or periscopes allowing an inspection of a person seeking admittance, or the delivery of messages or the like, and presenting a pleasing appearance harmonizing with the exterior of a door or wall in which the device is used.

It is the principal object of my invention to provide a device of this character with a closing disc for the observation opening automatically returning into its closed position after each operation, and equipped with an automatically operating locking device.

Another object of my invention is the provision of a device of this character of comparatively simple and therefor inexpensive construction adapted to fit any door or wall, and firmly held in position thereon, allowing an adjustment to suit the thickness of the material of door or wall and locking in its adjusted position.

A further object of my invention is the provision of an observation device of this type equipped with a closing disc falling into its closing position by its own weight, while its opening movement is suitably limited.

These and other objects and advantages of my invention will become more fully known as the description thereof proceeds and will then be specifically defined in the appended claims.

In the accompanying drawing, forming a material part of this disclosure:

Fig. 1 is an inner front elevation of my novel and improved observation device.

Fig. 2 is an end or edge view thereof, partly in section.

Fig. 3 is an outer or front elevation of the device.

Corresponding and like parts are referred to in the following description and indicated in all the views of the drawing by the same reference characters.

Referring to the drawing, the observation device comprises an outer tubular body 10 bevelled on its outer face, as at 11, and having an inner socket member 12 provided with an outer thread allowing the introduction of the body through a suitable opening provided

in a door and wall at a convenient distance above the floor holding and securing the device therein.

Upon the threaded socket member 12 a ring 13 is screwed allowing an adjustment of the device to doors or walls, etc., of any thickness of material such as for instance wood or metal. In its adjusted position the ring 13 is securely held in place by means of suitable fastening means passed through openings 14.

The inner end of socket 12 has projecting therefrom at a point of its face a pin 15 and a hook 16 spaced from said pin and below the same.

A disc 17 is pivotally attached, as at 18, near its upper end to the inner end of socket member 12, and has near its pivot point a curved recess 19 adapted to be engaged by said pin 15, for limiting the inward movement of the disc 17 constituting cover for the central peep opening in body 10.

A latch 20 is pivoted at its outer end, as at 21, to the disc 17 near its outer periphery and in a plane with hook 16. The opposite end of latch 20 is hook-shaped, as indicated at 22, while a knob 23 projecting intermediate the ends of said latch 20 therefrom, allows a constant operation of the same.

A guide or guard 24 allows the passage of the latch 20, and limits its upward and downward movement.

The front face of disc 17 is provided with a suitable grille 25 or other suitable open or closed work.

The operation of my device will be entirely clear from the above description and on hand of the drawing. If it is desired to make an observation, the resident disengages latch hook 22 from hook 16 by lifting latch 20 by means of knob 23 and rotates disc 17 about its hinge 18, whereby the outer periphery of disc 17 will engage pin 15 and limit the turning movement of the disc. After the observation or exchange of messages have been completed, the observer simply lets the disc drop under its own weight whereupon the hook 22 will automatically engage hook 16 and lock the disc in its position in recess 19 to ensure the locking.

It will be clear that the downward or up-

ward movements of the latch will be suitably limited by guide or guard 24.

The disc 17 may have its outer face provided with an ornamental grille as shown or the grille may be open work, and in this instance provided in socket 12.

It will be understood that I have described and shown the preferred form of my device as an example only of the many ways in which the same may be practically constructed, and that I may make such changes in the general arrangement and in the construction of the minor details thereof without departure from the spirit of my invention, as come within the scope of the appended claims.

Having thus described my invention, what I claim as new, and desire to secure by Letters Patent is:

1. Observation device comprising a body having a centrally located peep opening and means for securing and holding said body to a support, said means allowing an adjustment to the thickness of the material of said support, a cover for said peep opening pivotally attached to said body, and having a recess in its periphery, said cover allowing a turning about its pivot to uncover the peep opening, a hook on said body, and means on said cover for engaging said hook to lock said cover automatically in its closing position after said dropping into closing position under its own weight, and a pin on said body adapted to engage the peripheral recess of said cover.

2. In an observation device of the character described, a body having a central peep opening adapted to be positioned in a door opening, means for adjustably holding said body in said opening, a cover eccentrically pivoted on said body said cover having a peripheral recess, a pin projecting from said body adapted to engage said recess for limiting the inward movement of said cover, the outward movement thereof being limited by the engagement of the outer periphery of said cover with said pin, a hook on said body, a latch pivoted at one end to said cover at a point opposite to said hook, a guard for limiting the vertical movements of the latch, a hook on said latch opposite to its pivot point adapted to engage said body hook automatically upon the falling of said cover into its peep opening closing position under its own weight, and a knob on said latch for operating the same to allow a turning of said cover about its pivot into its opening uncovering position, and a grille formed with said cover.

Signed at New York, in the county of New York and State of New York this 30th day of October A. D. 1928.

KARL BAUER.
